(57) CLAIM

The ornamental design for a sticker set for game console, as shown and described.

DESCRIPTION

FIG. 1 is a front view of a sticker set for game console showing my new design;

FIG. 2 is a perspective view of the sticker set for game console thereof, shown as a portion removed from the set in an alternate configuration of use, applied to an environmental game console.

FIG. 3 is a perspective view of the sticker set for game console as seen in FIG. 1, shown as a portion removed from the set and in an alternate configuration of use, applied to an environmental game console.

FIG. 4 is a front view of the sticker set for game console as seen in FIG. 1, shown as a portion removed from the set and in an alternate configuration of use, shown applied to an environmental game console.

FIG. 5 is a front view of the sticker set for game console as seen in FIG. 1, shown as a portion removed from the set and in an alternate configuration of use, applied to an environmental game console; and,

FIG. 6 is a front view of the sticker set for game console as seen in FIG. 1, shown as a portion removed from the set for clarity of disclosure and in an alternate configuration of use, applied to an environmental game console.

The broken lines shown in the figures are for the purpose of illustrating environmental subject matter only and forms no part of the claimed design.
